UNITED STATES PATENT OFFICE.

THOMAS J. CORNING, OF SAN JOSE, CALIFORNIA.

BALING-PRESS.¶

SPECIFICATION forming part of Letters Patent No. 363,365, dated May 24, 1887.

Application filed March 14, 1887. Serial No. 230,814. (No model.)

To all whom it may concern:

Be it known that I, THOMAS J. CORNING, a citizen of the United States, residing at San José, in the county of Santa Clara and State of California, have invented a certain new and useful Improvement in Baling-Presses; and I do hereby declare that the following is a full, clear, and exact description of the invention, which will enable others skilled in the art to 5 to which it appertains to make and use the same, reference being had to the accompanying drawings, and to the letters of reference marked thereon, which form a part of this specification.

15 My invention relates to improvements in baling-presses, the several features of which will be fully hereinafter set forth and claimed.

The invention involves the mechanism for actuating the plunger.

20 The mechanism is illustrated in the accompanying drawings, in which—

Figure I is a side view of the baling-press with a portion of the side cut away. Fig. II is a top view of the same with a portion cut 25 away on the line x, Fig. I. Fig. III is an under view of the pitman, spring, and its attachment to a broken portion of the plunger-head.

Like letters designate like parts throughout 30 the several views.

The frame A is in general construction like the horizontal baling-presses in use. It consists of an open frame to the right to support the operative parts, a top opening, B, through 35 which to feed the material, and a compression-chamber with orifices in the sides, through which the wires are introduced to do the binding. The plunger C is like a quadrangular box with an open end, and to the closed end 40 of which is attached the bearing-block E. To this block the pitman D is held by a pin. The pitman is of the form shown at Fig. 3, the ends being rounded vertically. To the under side is attached the slotted pin m. Beneath 45 the bearing-block E, against the plunger-head, is attached the block F, and to this is secured the flat steel spring G, whose free end occupies the slot of the pitman-pin. The plate J is supported on the shaft L, which is 50 held in bearings I, attached to the top and bottom of the frame. To this plate is to be attached the beam K, and to this a horse is hitched for the purpose of operating the baling-press. The plate J has a plane surface at 55 a right angle to the beam or pole, with bear-

ing-notches s at both ends and projections t beyond the bearing-surfaces. The function of the flat spring G is to hold the pitman at the longitudinal vertical center of the frame and that of the axis of the shaft. The effect 60 of this is to hold the free end of the pitman against the plane surface of plate J and cause the rounded end thereof to enter the notches as the same comes opposite. At Fig. I the plunger is shown in the position as it is thrown 65 back by the resilience of the compressed hay, the head of the pitman resting in the notch. The dotted lines at Fig. II show the position of the plunger when the stroke is completed and is about being disengaged from the plate 70 by the points t, bearing against the side of said pitman. When the rebound of the plunger takes place, the movement is arrested by the blocks, O O, attached to the bottom and top of the frame.

The operation is thus: The plunger being in position, as shown in Fig. I, hay is put into the chamber, a half-revolution is given by the operative beam, the rebound carrying the plunger and the pitman back along the face 85 of the plate to enter the notch, and the beam is given a reverse movement, and thus the hay is packed within the compression-chamber, and from which the bale is withdrawn through a suitable door.

I would not be understood as restricting my invention to the mechanism as shown and described, but would have it understood that the spring-actuated pitman in its relation to the face and notches of the operating beam or 90 lever is the essential feature of my invention.

Having fully described my invention, what I claim, and desire to secure by Letters Patent, is—

1. In a baling-press, the draft-pole, comprising beam and plate, and the pivotal spring-actuated pitman, combined with the plunger, substantially as set forth.

2. In a baling-press, the combination of the operating-beam K with plate J, having 100 notches s, pitman D, bearing-block E, plunger C, block F, and flat spring G, substantially as set forth.

In testimony that I claim the foregoing as my own I affix my signature in presence of 105 two witnesses.

THOMAS J. CORNING.
